UNITED STATES PATENT OFFICE.

GUSTAVE SCHWAB, OF NEW YORK, N. Y., ASSIGNOR TO HELENE SCHWAB,
OF SAME PLACE.

SUPPORT FOR PHOTOGRAPHIC ALBUMS.

SPECIFICATION forming part of Letters Patent No. 542,113, dated July 2, 1895.

Application filed August 16, 1894. Serial No. 520,477. (No model.)

To all whom it may concern:

Be it known that I, GUSTAVE SCHWAB, a citizen of the United States, residing at New York, in the county and State of New York, have invented new and useful Improvements 5 in Supports for Photographic Albums, of which the following is a specification.

The object of this invention is to provide a novelty in supports for albums and the invention resides in the novel features of construction set forth in the following specification and claims, and illustrated in the annexed drawings, in which—

Figure 1 is a side elevation of an album on a support sectioned along x x , Fig. 2, the album being closed. Fig. 2 is a rear elevation of Fig. 1. Fig. 3 is a view similar to Fig. 1, the album being open. Fig. 4 is a section along y y , Fig. 3. Fig. 5 is a section along z z , Fig. 4. Fig. 6 is a detail plan view of a detent or stop. Fig. 7 is a side elevation of Fig. 6.

The support consists of an easel or frame 1 having the swinging leg 2, jointed to back 25 piece 3, secured by side pieces 4 to frame 1. The back 3, with side pieces 4, form a box or receptacle in which photographs can be stored. A music-box may also be contained in the receptacle. A cover or lid 5 may be used to 30 close the receptacle. A plate or front piece 6 may separate the interior of box 3 4 from the album 7.

The easel is provided at its upper portion with hooks 9 and at its lower portion with a shelf 10 and on the under cover of the album are secured eyes 8 for detachably connecting said album to the hooks 9 on the easel. When the eyes 8 are made to engage the hooks 9, the back of the album rests upon the shelf 40 10, as shown in Fig. 1. Said eyes project above the upper or free edge of the under cover, so that they can be readily brought in engagement with the hooks 9, and that the album can be readily disengaged from said 45 hooks when it is desired to inspect the pictures of the album by placing said album on a table or supporting it in any other desirable manner. It must also be remarked that said eyes do not interfere with the operation of 50 placing the album into a book case or otherwise disposing of the same in the manner in

which books are usually put away when the same are not used. At the same time when the eyes 8 are made to engage the hooks 9 the album can be opened and the pictures 55 contained therein can be conveniently inspected, and during this operation the back of the album is free to move in and out on the shelf 10 of the easel. Furthermore, when it is desired to change the pictures in the album 60 or to insert new pictures, this operation can be performed by unhooking the album and placing it down upon a table or upon one's lap, where it will lay flat like an ordinary album.

Projecting through front piece 6 is a finger or arm 11, extending from spring-strip 12 fixed to back 3. When the weight of the album rests against finger 11 to depress spring 12 toward back 3, the arm 13 of the lever 13 70 14 is freed, so that the lever can be moved on its fulcrum 15 by the action of spring 16, Fig. 4, to carry its arm or nose 14 into engagement with wheel 17 or with a recess 19 in said wheel to stop the latter rotating. This 75 wheel 17 forms part of the well-known mechanism of the familiar musical box. When the spring 12 is sufficiently relieved from the weight of the album by the latter being wholly or partly opened, said spring 12, with finger 80 11, rises to move lever 13 14 to its releasing position against the action of spring 16, so that the music-box will be free to play.

A key 18 can be suitably applied for winding up the music-box.

The music-box can be made to only partly fill the receptacle 3, 4 so that room will be left therein for storing pictures, photographs or other articles.

By covering or padding the shelf 10 with a 90 material which will match or harmonize with the cover of the album a tasty appearance is secured.

What I claim as new, and desire to secure by Letters Patent, is—

1. An easel provided at its upper portion with hooks 9 and at its lower portion with a shelf 10 in combination with an album having attached to the upper or free edge of its under cover eyes 8 in such a position that the album can be readily attached to or detached 100 from the easel and that when these eyes are

made to engage the hooks 9, the back of the album rests loosely upon the shelf 10 and is free to move in and out on the same substantially as shown and described.

5 2. The combination of an easel provided with a receptacle fixed to the back thereof, an album having attached to the upper edge of its under cover means for detachably connecting it to the easel, a music-box arranged 10 within the receptacle, and a detent controlling the starting and stopping mechanism of the music box, said detent being held out of engagement with said mechanism by the weight of the closed album and operating to 15 release said mechanism when the album is opened, substantially as described.

3. The combination of an easel provided at its upper end with hooks and its lower end with a shelf adapted to support the back of

an album, an album having attached to the 20 upper edge of its under cover means for detachably engaging said hooks, a music box arranged within the receptacle, and a spring detent normally projecting through the receptacle into engagement with the album and 25 controlling the starting and stopping mechanism of the music box, the weight of the closed album holding said detent inoperative and the shelf operating to throw the album out of contact with the detent when the al- 30 bum is opened, substantially as described.

In testimony whereof I have hereunto set my hand in the presence of two subscribing witnesses.

GUSTAVE SCHWAB.
